JACKET OR SIMILAR ARTICLE

Helen Macy, New York, N. Y.

Application July 8, 1954, Serial No. 31,338

Term of patent 14 years

(Cl. D3—4)

FIG. 1

To all whom it may concern:

Be it known that I, Helen Macy, a citizen of the United States of America, residing at the city, county, and State of New York, have invented a new, original, and ornamental Design for a Jacket or Similar Article, of which the following is a specification, reference being had to the accompanying drawing, forming part thereof.

Fig. 1 is a front view of a jacket showing my new design, the pocket flap being in closed position;

Fig. 2 is an enlarged fragmentary view of the jacket shown in Fig. 1 with the pocket flap in open position; and Fig. 3 is an edge view of Fig. 2.

The back of the jacket is conventionally plain and the essential feature of the design resides in the pocket member shown in full lines.

I claim:

The ornamental design for a jacket or similar article, substantially as shown and described.
